UNITED STATES PATENT OFFICE.

GEORGE M. LESHER, OF NEWARK, NEW JERSEY.

CENTRIFUGAL SEPARATOR.

1,026,271.

Specification of Letters Patent.

Patented May 14, 1912

Application filed October 10, 1911. Serial No. 653,824.

To all whom it may concern:

Be it known that I, GEORGE M. LESHER, a citizen of the United States, residing at Newark, in the county of Essex and State of New Jersey, have invented certain Improvements in Centrifugal Separators, of which the following is a specification.

The objects of this invention are to provide in the bowl of a centrifugal separator a plurality of disks adapted to separate the liquid into layers, which disks have their lower edges arranged at different radial distances from the central axial line of the bowl; to locate said lower edges at a distance above the bottom of the bowl and thus enable the liquid to feed directly into all the spaces between said disks; to locate said lower edges at different distances above the floor of the bowl so that the lighter portion 10 of the fluid, moving horizontally inward, will naturally enter the spaces between the disks; to increase outwardly the height from the floor of the bowl of said lower edges of such successive disks at the bottom of a 20 bowl, so as to provide more space radially outward toward the periphery of the bowl; to secure a separator bowl of high efficiency and simple construction, and to obtain other advantages and results, as may 30 be brought out in the following description.

Referring to the accompanying drawings, in which like numerals of reference indicate the same parts throughout the several views, Figure 1 is a side elevation of a centrifugal bowl embodying my improvements; Fig. 2 is a central vertical section of the same taken on line A—A of Fig. 4, looking in the direction indicated by the arrow; Fig. 3 is a portion of a section similar to Fig. 2 40 illustrating the application of my invention to the top disks of a bowl; Fig. 4 is a plan of the bowl with its cover and interior disks removed, showing the center tube, feed plate and wings thereon; Fig. 5 is a sectional view of a portion of the feed plate showing one of its upper and lower wings in side elevation; Fig. 6 is a plan of a certain disk; Fig. 7 is a detail view illustrating certain means for holding the disks spaced 50 from one another; Fig. 8 is a central vertical section similar to Fig. 2, illustrating a slightly different construction, and Fig. 9 is a plan of the same with the cover removed.

55 In said drawings, 1 indicates a centrifugal separator bowl having a spindle and

bottom 3 with an interiorly-threaded peripheral flange 4 by which it can be screwed onto the cylindrical body 5 of the bowl and firmly soldered thereto as usual.

A removable feed tube 6 is arranged centrally and axially of the bowl, said feed tube having at its lower end a radially projecting feed plate 7 which is held a little above the floor of the bowl, parallel thereto, and extends at its edge close to the side wall of the bowl, being preferably notched at one point of said edge, as at 8, to receive a projection 9 on the bowl body and thus be keyed to rotate with the bowl. Said feed tube 6 is perforated adjacent to its feed plate 7, as at 10, and said feed plate is also perforated outside the tube, as at 11, for the passage of liquid to be separated. The bowl body 5 is exteriorly threaded at its top to receive the correspondingly threaded flange 12 of a cover 13, which cover is in general conical with a cylindrical portion 14 at its top whose side walls lie at a little distance from the central tube 6 and whose top is 80 apertured to fit around the said tube.

Within the bowl and above the feed plate 7 are arranged interior disks which surround the central feed tube 6 and have each an annular downwardly flaring flange or conical portion, said disks being nested in a vertical series within the centrifugal bowl. The lowest disk has its peripheral edge a sufficient distance above the feed plate 7 to allow proper passage of the fluid to be separated, and is at said edge of much smaller diameter than the diameter of the bowl. Preferably the next disk is at its peripheral edge of greater diameter so as to lie nearer the walls of the bowl, and similarly each next outward disk is of greater diameter than the preceding one, so that the lower edges of the disks form a stepped series extending from the lowest disk outwardly to the walls of the bowl, as shown. This series of lower edges may extend outward in an inverted conical surface, as shown, or in any other shaped surface which can be obtained by varying the slant heights of the conical disks. Particularly in clarifying or removing a sediment from a liquid, the form shown in the drawings is especially desirable, as it affords ample space for the accumulation of sediment next the walls of the centrifugal bowl.

110 Preferably, the lower edges of the disks and the under surface of the lowest disk en-

gage wings 15 which are fixed upon the feed plate 7, and so shaped at their upper edges as to properly support the disks. These wings 15 extend from the feed tube 6 outward to the edge of the feed plate and are of any suitable number, as the four shown in Fig. 4. Other wings 16 are arranged upon the bottom of the feed plate 7 to space the same from the floor of the bowl.

10 The disk or disks of largest diameter may terminate short of the wall of the bowl, as illustrated by the disk 17 in Fig. 8, or may seat at its peripheral edge upon a shoulder 18 in the side walls, as shown by the disk 19 in Fig. 2. In the former case up-flow will take place between the edge of the disk 17 and the wall of the bowl, and in the latter case a series of apertures 20 must be provided in the disk for such flow. At the upper part of the bowl there may also be a stepped series of disks, if desired, as shown in Fig. 8, each next upper disk being at its peripheral edge of less diameter than the one below.

25 In any event, the top disk which is marked 21 in Figs. 2 and 8 has at its top a cylindrical neck 22 which divides the neck of the cover 13 into annular inner and outer flow spaces 23 and 24, respectively. From these flow spaces outlets 25 and 26, respectively, are provided for the escape of liquid, as is common, said outlets being in the neck of the cover. Each of the disks below said top disk has at its upper small end an inwardly extending horizontal flange which fits against the feed tube 6, and by means of these flanges the disks are preferably all loosely keyed to the feed tube, as shown at 27 in Fig. 4. Furthermore, these horizontal flanges of the disk are perforated, as at 28, to permit the up-passage of the light portion of a liquid to be separated.

Various disks of the series are spaced from each other and from the cover in any suitable manner, although I have shown it done by means of wings 29 on the top disk which engage the cover and spacing projections 30 on the next disk and every alternate one thereafter. These spacing projections I have shown formed by little strips of sheet metal having their ends thrust through slits in the conical portion of the disk and bent over flat against the other side, and said projections are suitably distributed to support 55 the disks. In the construction illustrated in Fig. 3, auxiliary wings 31 are of course arranged in alinement with the wings 32 on the top disk which have been already described in connection with the other figures 60 of the drawing.

In the operation of my improved separator, the liquid which is fed down through the tube 6 and up through the feed plate 7 is to a large extent separated into its light 65 and heavy portions before reaching the

disks at all, and the light portion passes through the holes of the lower disk and so on to the outlet at the top of the bowl. If the disks are arranged with their lower edges in an ascending stepped series, as shown, the partially separated heavier portion of the liquid finds a ready entrance between the successive disks of the series and is thus divided into thin layers between said disks, such layers being taken successively off of the inner periphery of an annular body of liquid imagined to be moving upward in the bowl. Finally the outer heaviest portion escapes through the openings 20 and is subjected to a last separation in passing down around the lower edge of the top disk and goes up between the same and the cover to its outlets 26.

If the top disks also form a stepped series, as shown in Fig. 3, this last separation of the heavy portion of the liquid is extended and made more effective because the stepped disks provide spaces for layers of the inwardly crowding lighter portions, where still further separation can take place and an opportunity be given for light particles to escape.

Having thus described the invention, what I claim is:

1. In a centrifugal separator bowl, a vertical series of disks having conical portions flaring downwardly outward and terminating at their edges at different radial distances from the axis of rotation of the bowl, said edges being free and spaced from each other and the other parts of the bowl, means for feeding liquid against said edges, and discharge means.

2. In a centrifugal separator bowl, a vertical series of disks having conical portions flaring downwardly outward and terminating at their edges at different radial distances from the axis of rotation of the bowl and at different heights from the floor of the bowl, said edges being free and spaced from each other and the other parts of the bowl, means for feeding liquid against said edges, and discharge means.

3. In a centrifugal separator bowl, a vertical series of disks having conical portions flaring downwardly outward and terminating at their edges at different radial distances from the axis of rotation of the bowl, the lower edges of said disks lying in a surface flaring upwardly outward and being free from other parts of the bowl so as to provide a flow space past themselves, means for feeding liquid against said edges, and discharge means.

4. In a centrifugal separator bowl, a vertical series of disks having conical portions flaring downwardly outward and terminating at their edges at different radial distances from the axis of rotation of the bowl, the lower edges of said disks lying in a

- 8
- substantially conical surface flaring upwardly outward and being free from other parts of the bowl so as to provide a flow space past themselves, means for feeding liquid against said edges, and discharge means.
5. In a centrifugal separator bowl, the combination with a central axial feed tube and suitable discharge means, of a vertical series of disks on said feed tube apertured adjacent thereto and having outer conical portions flaring downwardly outward and terminating at their edges at different radial distances from said feed tube, said edges being free and spaced from each other and the other parts of the bowl, means for feeding liquid against said edges, and discharge means.
6. In a centrifugal separator bowl, the combination with a central axial feed tube and suitable discharge means, of a vertical series of disks on said feed tube apertured adjacent thereto and having outer conical portions flaring downwardly outward and terminating at their edges at different radial distances from said feed tube and at different heights from the floor of the bowl, said edges being free and spaced from each other and the other parts of the bowl, means for feeding liquid against said edges, and discharge means.
7. In a centrifugal separator bowl, the combination with a central axial feed tube and suitable discharge means, of a vertical series of disks on said feed tube having flat apertured portions adjacent thereto and outer conical portions flaring downwardly outward and terminating at their edges at different radial distances from the feed tube and at different heights from the floor of the bowl, said lower edges lying in a surface flaring upwardly outward.
8. In a centrifugal separator bowl, the combination with a central axial feed tube and suitable discharge means, of a vertical series of disks on said feed tube having flat apertured portions adjacent thereto and outer conical portions flaring downwardly outward and terminating at their edges at different radial distances from the feed tube and at different heights from the floor of the bowl, said lower edges lying in a substantially conical surface flaring upwardly outward.
9. In a centrifugal separator bowl, a disk having a downwardly flaring conical portion in impervious relation at its edges to the wall of the bowl and apertured at a distance from said edges, and a series of similar disks adjacent to said first-mentioned disk, the disks of said series decreasing in diameter away from said first-mentioned disk and being free at their edges from the other parts of the bowl so as to provide a flow space past themselves, means for feeding liquid against said edges, and discharge means.
10. In a centrifugal separator bowl, a disk having a downwardly flaring conical portion in impervious relation at its edges to the wall of the bowl and apertured at a distance from said edges, and a series of similar disks beneath said first-mentioned disk, the disks of said series decreasing in diameter downwardly and being free at their edges from the other parts of the bowl so as to provide a flow space past themselves, means for feeding liquid against said edges, and discharge means.
11. In a centrifugal separator bowl, a disk having a downwardly flaring conical portion in impervious relation at its edges to the wall of the bowl and apertured at a distance from said edges, a series of similar disks beneath said first-mentioned disk, the disks of said series decreasing in diameter downwardly and having their edges lying in a substantially conical surface.
12. The combination with a centrifugal bowl having a cover with a conical portion and a cylindrical top, of a top disk having a conical portion lying in said conical portion of the cover and a neck extending into said cylindrical portion, a series of disks below said top disk having conical portions which terminate at their edges at different radial distances from the axis of rotation of the bowl, and means for feeding liquid to said disks.
13. The combination with a centrifugal bowl having a cover with a conical portion and a cylindrical top, of a top disk having a conical portion lying in said conical portion of the cover and a neck extending into said cylindrical portion, a series of disks below said top disk having conical portions which terminate at their edges at different radial distances from the axis of rotation of the bowl and at different heights from the bottom of the bowl, said edges being free and spaced from each other and the other parts of the bowl, means for feeding liquid against said edges, and discharge means.
14. The combination with a centrifugal bowl having a cover with a conical portion and a cylindrical top, of a top disk having a conical portion lying in said conical portion of the cover and a neck extending into said cylindrical portion, a series of disks below said top disk having conical portions whose edges lie in a downwardly and inwardly converging surface, and means for feeding liquid to said disks.
15. The combination with a centrifugal bowl having a cover with a conical portion and a cylindrical top, of a top disk having a conical portion lying in said conical portion of the cover and a neck extending into said cylindrical portion, a series of disks below said top disk having conical portions

- whose edges lie in an inverted substantially conical surface terminating short of the floor of the bowl, and means for feeding liquid to said disks.
- 5 16. In a centrifugal bowl, a vertical series of disks having conical portions flaring downwardly outward and terminating at their edges at different radial distances from the axis of rotation of the bowl and at 10 different heights from its floor, wings extending across the stepped edges of said disks, and means for feeding and discharging liquid.
17. In a centrifugal bowl, a central axial feed tube with a projecting feed plate, a series of disks on said feed tube having conical portions flaring downwardly outward and terminating at their edges at different radial distances from said feed tube and at different heights from said feed plate, and 15 wings on said feed plate shaped at their upper edges to engage said edges of the disks. 20
